DISPENSING DEVICE

John W. Rich, Los Angeles, Calif.

Application June 25, 1951, Serial No. 233,300

1 Claim. (Cl. 222—390)

1

The present invention relates to dispensing from non-collapsible containers by forcible extrusion and more specifically to a dispensing attachment applicable to standard types of commercial containers or cans of shortening compounds, etc. of a pasty or viscous nature.

The principal object of the invention is to provide dispensing means which can be constructed to fit and readily be attached to, or mounted on, the standard sizes of containers, usually cans, in which substances of the nature above mentioned are marketed. Another object is to make such an attachment which will substitute for the original cover of a container and form a tight closure therefor when not being operated to dispense the contained material. In its broader aspect, the present invention represents species or modifications of that disclosed in inventor's copending application for patent Serial No. 216,794 filed March 21, 1951, now abandoned.

The foregoing objects are attained by providing certain novel forms of dispensing attachments fitting on and within a container, in lieu of its original cover, including means for securely clamping them in position. These and other advantages are provided by the structural embodiments of the invention hereinafter described and claimed and illustrated in the accompanying drawings, where:

Figure 1 is a side view of one form of the attachment as combined with a container;

Figure 2 is a top view of same;

Figure 3 is a vertical section through the combined container and attachment on the line 3—3 of Figure 2;

Figure 4 is a detail showing the extruding piston shown in section in Figure 3;

Figure 5 is a view in perspective of another form of attachment in mounted position on a container;

Figure 6 is a vertical section viewed on the line 6—6 of Figure 5, and

Figure 7 is a horizontal section viewed on the line 7—7 of Figure 6.

For the purposes of this disclosure, the novel structures are shown as in position, or mounted on, a conventional pound or quart can C from which the original cover has been removed.

In the species of Figures 1 to 4, the dispensing device which mounts on the can as a substitute for the cover consists of a cylindrical sleeve 10 designed to telescope within and throughout the depth of the can adjacent its inner wall. At the proper place in its length, sleeve 10 is provided with an external circumferential shoulder 11 (Figure 3) the lower edge of which engages the upper edge of the container or can 10 and serves as a stop for gauging proper insertion of the sleeve 10 within the can. The shoulder 11 is straddled by a split clamping band 12 having an upper lip 12a in engagement with the upper edge of shoul-

2

der 11 and a somewhat shorter lower lip 12b which engages the upper outer surface of can C. Many such cans are formed with a marginal rib below which the lip 12b is designed to engage as shown. 5 The clamping band 12 is preferably attached to sleeve 10 at a point diametrically opposite its split or point of separation. It is preferably formed of somewhat resilient plastic material, or metal, thus providing opposite arcuate arms 10 which are drawn together to a clamping relation with can C as by means of a toggle clamp 13 (Figure 1). The clamping band 12 is intended to be grasped in a user's hand during operation of the device and for that reason is preferably formed with a slightly concaved and corrugated or ribbed outer surface, as best shown in Figure 1, to afford a secure grip.

The dispensing or extruding mechanism mounted on and within sleeve 10 consists of an 10 outlet tube 14 which extends the length of the sleeve at one side. The upper end of this tube has a right angled extension 15 leading to an extrusion opening in sleeve 10 located above band 12. This opening is located between external 15 parallel guides 16 on the sleeve which retain a 20 slideable shut-off 17. Tube 14 also serves to guide and prevent rotation of a plunger or piston 18 which has an aperture 18a receiving tube 14. Piston 18 is preferably formed with radial reinforcing ribs 18b extending from its central opening and carries a flexible washer 19, the periphery of which wipes the inner surface of sleeve 10. The central opening 20 of piston 19 is screw threaded for engagement with a central screw 25 threaded post 21 on which it travels. The upper end of post 21 is fixed to a cover plate 22 which seals the upper end of sleeve 10 in rotatable contact with its upper edge. A clamp screw 23 threaded into a squared end on post 21 which 30 fits a complementary aperture in cover 22 is preferably used to unite the post and cover. The cover 22 is preferably provided with a crank knob 24 and with suitable directional indexes in its circumference, as at 25, designed to be rotated into registration with an index arrow 26 on sleeve 10. Air vents may be provided in the upper part of sleeve 10, as at 27, to permit escape of air when piston 18 is moved down to the can load at initial operation, the piston being 35 then at the top of post 21.

With the above embodiment of the invention, the extruding mechanism comprising sleeve 10 and parts mounted thereon is telescoped into a full can from which the original cover has been 40 removed, to the position seen in Figure 3. The clamping band 12 is then locked by means of the toggle 13 thereby firmly uniting the can and extruding mechanism. Any material displaced by insertion of the sleeve together with tube 14 45 and post 21 will be accommodated within the sleeve above the can edge but below the level of

the air vents 21. The device may then be operated by grasping the clamp band 12 in one hand and turning the cover 22 clockwise with the other by means of knob 24 thereby turning post 21 also. This will cause piston 18 to be moved downward from its initial position at the top of post 21 into contact with the can contents. Further movement will compress the contents forcing some through tube 14, 15, to the outlet. The pitch of the threads on post 21 is so gauged as to cause a predetermined amount of material to be forced out by travel of piston 18 at each full turn of cover 22. By way of example, the cover in Figure 2 is shown as carrying one possible directional form of index.

In the species illustrated by Figures 5 to 7, a cylindrical sleeve 30 telescopes within a can C, as in the first described species. An offset shouldered clamping band 31 which is preferably fixed to sleeve 30 at one side thereof, as at 32 (Figure 6), extends around the can and is split to form two somewhat resilient arcuate arms terminating in outstanding lugs 33. The inner side of the shouldered edge 34 of the offset band 31 rests on the upper edge of the can C and serves as a stop which gauges correct telescopic insertion of sleeve 30 within the can. A clamp bolt 35 or the like connects the lugs 33 and serves to clamp the arms of band 31 firmly on the can. As a component part thereof sleeve 30 carries a vertical wing or baffle 36 extending radially inward from the inner wall of the sleeve to which it is fixed as by keying, as shown. The lower edge of baffle 36 is even with the lower edge of sleeve 30 but at the upper edge baffle 36 is extended somewhat above the sleeve as seen in Figure 6.

The sleeve 30 carries a lid or cover 37 with a depending skirt 38, the lower inner side of which has a friction fit with the outer side of sleeve 30 and with the shoulder 34 of clamping band 31. Cover 37 is, therefore, positioned above the top of can C with the greater portion of skirt 38 above the top edge of sleeve 30. In that portion, the skirt 38 is provided on one side with a dispensing aperture 39 from which contained material can be extruded. The cover 37 is preferably formed with a countersunk segment 40 housing a swinging arm 41 which extends radially from the center of the cover 37. Arm 41 has a depending closure lip 42 in frictional engagement with skirt 38 and movable over or away from aperture 39 as by means of a thumb piece 43. The center of the cover 37 is formed with a perforation receiving a reduced screw threaded spindle 44 on the upper end of a depending central post 45. Post 45 is preferably formed with a flared base or foot 46 adapted to contact the bottom of can C. Post 45 carries a vertical wing or baffle 47 which is fixed thereto and extends radially therefrom to approximate contact with sleeve 30. The upper edge of baffle 47 is preferably fixed to cover 37 too and is positioned adjacent to aperture 39. Cover 37 is counter-sunk around the opening for spindle 44 to house the trunnion 48 on a screw nut 49 on spindle 44. Trunnion 48 serves as the pivot for arm 41 and nut 49 locks post 45 and wing 47 securely in position on cover 37.

Clamping of band 11 will clamp or lock can C to sleeve 30 so that the two constitute a unit. The wing or baffle 36 on sleeve 30 extends approximately the radius of sleeve 30 into substantial contact with post 45. Therefore, can C and sleeve 30 can be rotated within cover 37 to move baffle 36 relatively to baffle 47. As cover 37 is above the

top of can C space is provided there for receiving material forced out when the device is inserted in a full can and for material under pressure during operation. This space is included by the baffles 36 and 47 which extend above the can top, as seen in Figure 2. Like the species first described, the device is intended to be mounted on an open full can as a unit, the sleeve 30, etc. being pressed down into it until the under side of shoulder 34 contacts the edge of the can top. The clamp band 31 carries scale markings 50 which are graduated in a manner to indicate quantity of material which will be extruded from aperture 39 at each step on the scale upon rotation of band 31 with respect to cover 37 the skirt 38 of which carries a complementary index arrow 51.

With aperture 39 open, extrusion of material is effected by clockwise rotation of can C with respect to cover 37, can C being, in effect, a unit with sleeve 30 and baffle 36. Should each division on scale 50 represent a tablespoonful of material, rotation of can C by one hand while the other holds cover 37 against rotation will bring successive marks on the scale to the arrow and cause a tablespoonful of material to be extruded for each division passed. As baffle 47 is a unit with cover 37 and baffle 36 is a unit with can C and sleeve 30, clockwise movement of baffle 36 will cause material confined between fixed baffle 47 and movable baffle 36 to be put under compression and forcibly extruded through aperture 39.

Accordingly, the invention presents a simple and efficient dispensing device adapted for telescopic connection with standard types of containers in substitution for the original cover. It affords complete protection to contained material and provides for dispensing it in accurately measured quantities without contact with the user's hands.

The preferred embodiments of the invention herein disclosed are subject to variations in structural details without departure from the scope of the invention as hereinafter claimed.

What is claimed is:

A dispensing attachment for open top cans containing viscous matter, comprising a cylindrical sleeve having a lower portion adapted to be telescoped within a can, a circumferential shoulder on the outer side of said sleeve adapted to engage a can edge and gauge depth of insertion of the sleeve therein, a split clamping band straddling said shoulder and providing arcuate arms adapted to be clamped to a can in encircling relation thereto, said sleeve being formed with an outlet aperture in its portion above said shoulder, an outlet tube leading from said outlet to the lower end of said sleeve and having a straight portion in spaced relation thereto, a central threaded post fixed to the cover and extending downward within the sleeve in parallel relation to said straight tube position, a piston threaded on said post and formed with an aperture slidably engaging the straight tube portion, and means for rotating the cover and post to effect axial movement of the piston.

JOHN W. RICH.
